(57) **CLAIM**

The ornamental design for a display screen with graphical user interface as shown and described.

DESCRIPTION

FIG. 1 is a front view of a display screen with graphical user interface showing our new design; and, FIG. 2 is a front view of a display screen with graphical user interface showing an alternative embodiment of our new design.

The dual broken lines at the perimeter of the figure illustrate the display screen and the remaining broken lines illustrate portions of the graphical user interface. None of the broken lines form part of the claimed design.
